DEEP WELL PUMP

Roger W. Schoen, Mineral Wells, Tex., assignor to Alco Valve Company, University City, Mo., a corporation of Missouri

Application August 13, 1953, Serial No. 373,955

10 Claims. (Cl. 103—46)

The present invention relates to a deep well pump, and especially a pump of the hydraulic type actuated by a column of power oil conducted from the surface down to the bottom of the well, at which latter point the pump is located, and which pump includes piston means and valving mechanisms that alternately port pressure from the power oil to and from one face of the power piston, so as to produce the reciprocating movement of the pump rod.

It is an object of the invention to improve the pumping mechanism so as to enable it to be contained within a smaller space than heretofore. Another object is to provide a pump of this kind which may be assembled and disassembled readily with a minimum number of tools of a minimum number of different characteristics.

A further object is to provide a reversing valve mechanism assembled with the pumping mechanism so that there is a mechanical reversing of the reversing valve mechanism at the end of each stroke of the piston. Also, it is an object to provide a pump mechanism that will not stop on dead center, but rather is stall-proof.

Another object is to have a pump with relatively slow pump stroke and relatively fast return.

Other objects will appear from the fuller description to follow:

In the drawings:

Figures 1 through 5 represent successively lower parts of the pump motor and pump mechanism at the bottom of the well, shown in vertical diametrical section, there being some overlap in the several views so as to assure completeness of disclosure;

Figure 6 is a transverse section on the line 6—6 at the top of Figure 1 (in all the transverse sectional views the well tubing is omitted);

Figure 7 is a transverse section on the line 7—7 of Figure 1;

Figure 8 is a transverse section on the line 8—8 of Figure 1;

Figure 9 is a view partly in section of the upper head of the pump;

Figure 10 is a transverse section on the line 10—10 of Figure 1;

Figure 11 is a somewhat diagrammatic view of the valving apparatus that appears in the lower half of Figure 1;

Figure 12 is a transverse section on the line 12—12 at the top of Figure 2;

Figure 13 is a transverse section on the line 13—13 of Figure 2;

Figure 14 is a bottom plan view of a spacer and sealer member at the lower end of the valve mechanism;

Figure 15 is a vertical section of the spacer and sealer taken on the line 15—15 of Figure 14;

Figure 16 is a transverse section through the pump taken on the line 16—16 at the upper part of Figure 2;

Figure 17 is a transverse section on the line 17—17 of Figure 2; and

Figure 18 is a transverse section on the line 18—18 of Figure 2.

2

The pump will be described as an oil pump, with the understanding that other fluids may be used. A well tubing T has been illustrated to show the disposition of the pump, the pump being inserted into the tubing and lowered down from the surface. The diameter of the tubing has been exaggerated for clarity in drawing. As is known in this type of pump, a power fluid tube 20 leads down from the surface to conduct power oil down, which power oil is put under pressure by an appropriate pressure generating mechanism at the surface, of which various types are known in the art; such as that illustrated in the application of John E. Dube and Roger W. Schoen, Serial No. 374,004 filed Aug. 13, 1953.

The power oil tube 20 is connected into the head 21 of the pump motor mechanism. This head, in turn, is threaded into the upper end of an outer barrel 22 that extends downwardly so that it may enclose the valving apparatus and the power piston motor apparatus for the pump. The lower end of the outer barrel 22 connects through a threaded removable closure 23 into a compound spacer device consisting of spacer tubes 24 and 241 adjustably connected together. The spacer tube 241 finally is threaded onto the upper end of one of the standard sucker rod pumps, here generally indicated at 25. Since this pump forms no part of the invention, which is primarily concerned with the power mechanism to reciprocate the pumps, the pump itself will not be described. Suffice it to say that a sucker pump pull rod 26 extends upwardly from the top of the sucker rod pump 25 and constitutes the piston or plunger rod of the sucker rod pump, which is reciprocated up and down so as to cause the oil to be lifted. The upper part of the pump 25, as it appears in Figure 5, has openings 28 that constitute the oil outlets by which the pumped oil is delivered into the well tubing T upon the successive strokes of the pump, to be conducted to the surface. It is, of course, well known in this art that there is some sort of sealing means between the oil being pumped to the surface and the well oil at the bottom of the pump.

40 The pull rod 26 is threaded at its upper end into a coupling 30 that, in turn, is threaded into the lower end of a tubular connecting rod 31. The upper end of the connecting rod 31 connects into a piston assembly. Actually, the upper end of the connecting rod 31 fits through the lower end of a fitting 32, which has an enlarged opening extending downwardly from its upper end to provide a shoulder to receive and hold an internally threaded ring 33 removably threaded onto the threaded end of the connecting rod 31. It will keep the connecting rod from pulling downwardly out of the union 32. Above the ring 33 there is another coupling 34 externally threaded into the upper open end of the union 33, so that it keeps the connecting rod from moving out of the upper end of the fitting 32. In turn, the upper end of the member 34 receives the lower end of a pipe 35, which latter is threaded into the member 34.

The upper end of the pipe 35 is threaded into a ring nut 36 which clamps a piston device 37 onto the pipe 35 between the member 34 and the ring nut 36. The piston device may be of any suitable construction or assembly. Above the nut 36 a coupling 38 is threaded onto the upper end of the tube 35. Its upper end, in turn, is threaded into a spring barrel element 39 for a purpose to appear.

65 The foregoing parts reciprocate with the sucker rod pump piston and provide an axial opening from the upper end of the cage 39 to the bottom end of the connecting rod 31.

The cage 39 is a part of an overtravel spring mechanism including a coil type overtravel spring 40 acting at its lower end against a retainer 41 of a cross-sectional shape illustrated in Figure 18. The upper end of the spring

40 acts against a shifter device 410 which is provided with a shoulder 42, by means of which it is retained in the upper end of the overtravel spring cage 39.

Except in cases of overtravel, the shifter device 410 will reciprocate with the connecting rod, and hence with the sucker pump.

Reverting to the lower end of the apparatus, as previously indicated, there is an adjustable tubular extension of the outer barrel 22 formed by the members 24 and 241, with which the sucker rod pump 25 is connected by the illustrated connections. This adjustable barrel, in turn, is threaded onto the connecting rod barrel 24. The adjustable barrel extension may regulate the relative positions between the sucker rod piston and cylinder (not shown), and the motor piston, to insure maximum sucker rod piston stroke.

The upper end of the spacer tube 241 has an extended internally threaded portion that receives the externally threaded lower end of the upper member 24. By this arrangement, the upper member 24 may be threaded into the lower member 241 a selected distance, after which the relative positions may be locked by a ring nut 43.

The upper end of the spacer tube 24 is threaded onto the retainer and closure 23. There is appropriate packing surrounding the connecting rod 31 in the lower end of this retainer 23, and there is additional packing likewise arranged at the upper end. Chevron packing is preferred for the upper packing.

An upper packing retainer and sealer 44 fits into the upper end of the retainer 23 and also is stabilized and sealed within the barrel 22. Suitable O-ring packing elements are provided at various points in the assembly as indicated.

The upper end of the retainer 44 fits into the lower end of an inner cylindrical barrel 46, and is caused to close the lower end thereof, by the retainer 23. The barrel 46 abuts on a firm packing 47; and it extends upwardly to form the cylinder for the piston 37. The inner barrel 46 likewise extends upwardly past the overtravel spring cage 39 and, at its upper end, seats around the lower reduced end of a centering spring cage 48, there being a suitable O-ring packing between the two, and the two also fitting firmly to transmit compressive forces axially between the two, with sufficient axial contact to resist lateral distortion of the assembly under compressive stress, which is likewise true of the fitting of the lower closure 44 and the inner barrel.

The centering spring cage 48 extends upwardly and, at its upper end, receives a sealing and spacing member 50 that appears in Figure 2 and separately in Figures 14 and 15. The centering spring cage 48 has a recess extending down from its upper end, which is shouldered at its lower end so as to receive the spacer 50, and provide secure fit preventing lateral distortion under compression. The spacer 50 has a plurality of projections or feet 52 extending downwardly from its lower surface. These projections have a somewhat lesser diameter than the main body of the spacer, so that they extend into the centering spring cage 48 below the shoulder. These feet portions 52 are separated so as to permit fluid flow, as will appear. The spacer 50 also has a plurality of more or less semi-cylindrical cut-outs 53 that extend vertically between the several feet 52, all for purposes to appear.

The upper end of the spacer member 50 has similar feet-like projections 54, but these extend cut to the diameter of the spacer, and thereby fit into a valve cylinder 55 so that the latter extends down onto the spacer 50 and yet so that there may be fluid flow assured at the top of the spacer 50 from the middle thereof to the surface of the cylinder 55. The cylinder 55 has a sealing fit onto the spacer 50 to resist lateral distortion under compression on the assembly.

The cylinder 55, which surrounds the valving mechanism and is permanently and solidly fitted onto a valve

body 56, extends upwardly and fits over and engages in abutting relation the upper head 21 of the pump device which is reduced in diameter within the outer barrel 22. As a matter of fact, reference to Figures 1 and 8 will show that there is a double reduction on the lower end of the head 21 so that the cylinder 55 will be spaced within the barrel 22.

Suitable O-rings as indicated may seal off the foregoing parts. The structure as described shows that the pump 25 is rigid with the spacer tube 241, and the latter is rigid with the spacer tube 24, once those two parts are secured in proper adjusted relationship. In turn, the spacer tube 24 is rigid with the packing retainer and closure 23 which, in turn, is rigid with the outer barrel 22, and the latter is rigid with the upper head 21.

Thus, if the foregoing parts are threaded tightly together, they will insure against change in the length of the pump structure.

Inside the foregoing barrel part, the packing retainer 23 and its upper packing head 44 are in fixed abutting relationship so that the member 44 can not move downwardly when the parts are secured together as aforesaid. Then the inner barrel 46 is in abutting relationship with the centering spring cage 48, and the latter is in abutting relationship with the spacer 50 which, in turn, abuts the valve cylinder 55, which latter is in abutting relationship with the upper valve head 21. We may comment that the valve body member 56 is also in abutting relationship with the spacer 50 and with the upper pump head 21. All of these parts have sufficient overlap to provide stability against lateral distortion when the upper head and lower closure 23 are tightened onto the outer barrel. However, the space between the outer and inner barrels is small, and even the distortion permitted by the outer barrel would not seriously interfere with the pump.

From the foregoing, when the upper pump head 21 is threaded into position in the barrel 22, the inner parts mentioned are rigid and are held against extending lengthwise.

By the foregoing arrangement, the parts may be secured together, but also may be readily disassembled with a minimum number of tools.

The spacer 241 has lateral ports 60 at its lower end which open into the well casing. There are other ports 62 of like character through the upper spacer tube 24, and at the top of the latter there are still more ports 63. This assures against the development of a confined space which could fill with oil and resist pump action. There can be no trapped oil within the spacer tubes around the connecting rod 31.

The lower spacer tube 241 is provided with opposed grooves 64 that are flats designed to permit application of a tool to this part for aid in detaching it from the associated parts.

Reference to Figures 2 and 3 will show that the inner barrel 46 is spaced inside the outer barrel 22 so that oil may pass between the two. The lower end of the inner barrel 46 has ports 66 so that such oil may flow into an annular space 67 forming a lower pressure chamber, and may act against a lower annular surface 68 on the member 32, which latter is assembled with the piston elements 37 so as to constitute with them a piston. The member 32 is slightly smaller than the inside of the inner barrel 46 and oil may flow around between these two parts until it reaches the piston member 37. This piston member may be an assembly of separate parts, if desired, but is shown as a single member. The total effective lower piston area, therefore, consists of an annulus, with the outer diameter equal to the inner diameter of the inner barrel 46, and its inner diameter equal to the outer diameter of the connecting rod 31.

The upper pressure or piston chamber 71 is within the inner barrel 46 above the piston. The upper surface 72 of the overcenter spring cage 39 constitutes one part

of the downstroke piston area. As noted, the actuator 41 does not have a tight fit with the associated elements, so that the oil may pass down within this part as well as within the overcenter spring cage 39. The retainer 41 has a plurality of more or less semi-cylindrical passages 74 (Figures 2 and 18) through it so that the oil may flow down into the interior of the hollow tube 35 that, in effect, constitutes the upper part of the connecting rod 31. Since these parts are secured together and have a common bore, this liquid may continue down until it reaches the head of the union member 30 which confines it at the bottom end of the hollow connecting rod 31. The total effective piston area for the top of the piston is the inner diameter of the inner cylinder 46.

It will be seen from the foregoing that the lower cylinder 67 is always in communication, with the space or passage 70 between the outer and inner barrels. This passage 70 continues upwardly inside the outer barrel 22, past the inner barrel 46, the cage 48, the fitting 50 and the valve shell 55, to the head 21, where it communicates directly with the power fluid pipe. This latter is accomplished by connection of the latter into a well 80 in the head 21, from which two passages 81 (Figures 1, 6, 8 and 9) extend downwardly and laterally to the reduced portion of the head 21, above the valve shell 55, which is the upper closure for the passage 70.

Assuming for the moment the same hydraulic pressure to exist in the cylinders 67 and 71, the piston would be driven downwardly because of the greater effective area on the upper side of the piston than on the lower side. This has been diagrammatically suggested by the arrows in the two pressure cylinders, with the broken line extended across the upper cylinder 71 to illustrate the larger piston area for the downstroke. This is evident because the lower area is merely the annular space between the connecting rod 31 and the barrel 46, whereas the top area producing the downstroke is the entire inner diameter of the barrel 46. The valving mechanism is designed to determine when the hydraulic pressure shall be admitted to both of these cylinders and when the pressure in the upper cylinder shall be exhausted.

In considering the valving mechanism, it is convenient to start at the top. The head 21 also includes so-called exhaust passages 85 that lead into the well casing so as to communicate with the oil being pumped or the production oil. These passages open through the bottom of the head 21, which head is provided with spaced feet 87 so that, although it is in contact with the upper surface of the valve body 56, it nevertheless does not obstruct the flow of fluid from the passages 85 outwardly and downwardly. As appears particularly in Figures 1 and 10, the valve body 56 in its upper end has two peripheral grooves 89 extending down for a certain distance whence they communicate with lateral ports 90 leading to the axial bore 91 through the valve body from end to end. Owing to the various and separate feet 87 on the bottom of the head 21, the particular orientation about its axis of the valve body 56 with respect to the head 21 is immaterial. There may always be oil flow communication between the passages 89 and 85.

The upper pressure cylinder 71 connects through a partition 93 in the centering spring cage 48. This partition 93 is shown in Figures 2 and 17. It has a plurality of holes 94 through it, so that it does not obstruct passage of fluid from the cylinder 71.

Above the partition is the centering spring chamber 95, the details of which are to be described. The centering spring chamber 95 is in continuous communication past the feet 52 on the sealing member 50, and thence vertically through the passages 53 and around the upper lugs 54, so as to be in constant communication with the lower end of the valve body 56.

While the valve, as such, is not a part of this present invention, its adaptation into this assembly is a part hereof. It need be described only diagrammatically insofar

as the particular construction of its portings is concerned. Figure 1 shows that the pressure oil passage 70 outside the valve cylinder 55 communicates through the cylinder 55 and the valve body itself at three points. The lowest of these is the passages 100. The middle one is the passages 101. And the upper one is the passages 102. By this arrangement, oil under pressure is always admitted into the central bore 91 of the valve body 56.

There are three valves in the axial bore 91 of the valve body 56. For this reason, there are two stop members pinned into the valve body. There is a lower stop member 105 that seals off the bottom part of the bore from the intermediate part. This stop 105 is held in place by a pin 106. There is also a stop seal 107 held in by a pin 108. The seal and stop 107 separates the intermediate valve chamber from the upper valve chamber. These stops separate three separate hydraulic valve systems.

Within the bottom valve chamber there is a mechanical valve 110. It has a depending valve stem and head that is latched into a valve stem extension 111. To this end, the lower end of the valve 110 has a reduced neck 112 and a head 113. The extension 111 has an enlarged head 114, having a recess for the head 113 in the reduced stem 112, with a lateral opening 115 to receive the stem 112, and a larger lateral opening 116 to receive the head 113. By this means the extension 111 may readily be laterally passed onto the valve head, and yet held so that movement up or down of the extension 111 causes corresponding movement of the valve. The fit of the head 114 within the fitting 50 prevents lateral detaching movement of these parts when they are in operating positions.

The member 111 extends down through the partition 93 and is joined to another valve stem extension 120 by means of a threaded collar 121 engaged over the lower threaded end of the member 111 and the upper threaded end of the extension 120. In the positions illustrated, the collar 121 passes freely through a center opening in the partition 93. The collar forms abutments for purposes to appear.

The stem 120 extends down freely through the actuator 41 in a manner sufficient to permit the passage of oil between the two. It has a length approximately equal to the stroke of the pump motor piston. At its lower end the member 120 is provided with a double nut 122-123 tightly secured to the end of the extension stem 120 so as to provide an adjustable shoulder abutment element for a purpose to appear. Figure 18 shows that the retainer 41 fits reasonably closely with a sliding fit onto the stem extension 120 so that the nut 123 may act as an abutment against the bottom surface of the retainer 41. The lower end of the valve stem 120 and the locking nuts 122 and 123 may move freely within the tube 35 of the piston, the union 34 and the connecting rod 31.

The centering spring chamber 95 contains spring actuated centering mechanism for the mechanical valve 110. There are two flanged, tubular, centering spring guides. The lower guide 125 rests on the upper end of the partition 93 without obstructing the vertical passages 94 therethrough. The lower end of a coil spring 126 rests on the guide 125. The upper end of the coil spring 126 rests on the upper guide 127 which impinges upon the feet 52 on the bottom of the spacer, which feet are provided so as to assure flow through the passages 53 and around the guide 127. The spring 126 is a compression spring normally urging the two guides 125 and 127 apart and into contact with the partition 93 and the spacer 50, respectively. The stem extension 111 passes through the guides and the spring. The head 114 and the upper end of the collar 121 are spaced apart a distance equal to the distance between the spacer 50 and the partition 93, so that the valve stem 110-111-120 is yieldably held in a middle position from which it may be displaced in

either direction, and toward which it will be urged to return by the spring 126.

The valve 110 has four lands thereon. They are, reading from bottom to top, the lands 130, 131, 132 and 133. Between the lands 130 and 131 there is a valve passage 134. Between the lands 131 and 132 there is a valve passage 135. Between the lands 132 and 133 there is a valve passage 136.

Below the land 130 the valve is open to the pressure within the upper cylinder 71. The space above the land 133 between it and the spacer 105 is similarly connected to the cylinder 71 by passages 138.

At this point, it is observed that the passage 138 is not illustrated completely, but is shown fragmentarily in a manner to indicate its presence. Actually, the passage extends to the surface of the valve body member 56, and thence by a groove on the valve body member that is enclosed by the cylinder 55. This groove extends parallel to the axis down to the space below the valve body. A dashed line indicates it. It will be seen that this dashed line also connects into a passage marked CYL, at the upper end of the valve body.

By the foregoing arrangement, the two opposite ends of the valve are always open to the pressure existing in the upper cylinder 71.

The mechanical valve 110 is designed to have three positions. It is illustrated in its intermediate or neutral position into which it is normally moved by the action of the centering spring 126. If the valve stem 120 is pushed upwardly, the collar 121 will impinge upon the lower guide 125, elevating the same against the spring 126 and causing the valve 110 to move to an upper position. In like fashion, if the valve stem 120 is pulled downwardly, it will, acting on the head of the extension 111, pull the upper guide 127 down, compressing the spring 126 and moving the valve 110 to a lower position.

In the middle position or neutral position illustrated in Figure 11, power oil is introduced by the passages 100 into the space 135, where it is trapped. Also, the oil at the pressure of the production oil in the interior of the well casing and carried down by the passages 85 is transmitted from above the valve body 56 through the passage 140 shown in Figure 10 and shown by a dashed line in Figure 11, to two passages 141 and 142 leading respectively to the valve spaces 134 and 136, in both of which it is then trapped.

If the mechanical valve 110 is moved upwardly until the two guides 125 and 127 abut, it will connect the power oil passage 100 through the valve passage 135 to work passages 143 that lead, as indicated by a dotted line, upwardly to the lower pressure chamber below the intermediate valve. At the same time, the upward movement of the mechanical valve 110 will cause the return line 141 to be connected through the valve space 134 to a passage 144 that is connected, as illustrated by the dot and dash line, into the upper pressure chamber of the intermediate valve. Hence, such shifting of the mechanical valve ports pressure or power oil to the bottom of the intermediate valve and connects the upper end thereof to exhaust. A consideration of the porting conditions when the valve 110 is lowered, until the two guides 125 and 127 are in contact, will demonstrate that the reverse porting of power oil onto the upper part of the intermediate valve and production oil pressure on the lower part will be produced. Also, whenever the mechanical valve 110 returns to neutral position, it hydraulically locks the pressures in the intermediate valve pressure chambers.

Power oil is continuously supplied through the ports 101 to the intermediate valve 150. The intermediate valve has four lands 151, 152, 153 and 154. These afford, respectively, a lower valve passage 155, a middle valve passage 156, and an upper valve passage 157. They also provide for upper and lower valve operating chambers connected respectively to the lines 143 and 144 that are controlled by the mechanical valve so as to position the inter-

mediate valve, as described. It is a two-position valve, illustrated in its lower position. Its primary function is to position the upper main valve by regulating the connections into the chambers above and below this valve.

- 5 And it functions to produce a relatively rapid action of the upper valve or main valve, avoiding its sticking in a mid-position.

In the lower position of the intermediate valve 150, illustrated, power oil enters the passages 101 and flows by the valve passage 156 to passages 160 that lead to the lower pressure chamber below the top valve. Meanwhile, the valve space 157 connects the passage 161 leading from the upper pressure chamber of the main valve to the return line 140 by means of a passage 162. There is a similar passage 163 also connected into the return line 140 which, in the lower position of this intermediate valve, is just below the land 152.

When the intermediate valve 150 is elevated to its upper position, the power oil to the passages 101 is cut off from the passage 160 and is introduced to the passage 161 leading to the top of the main valve. Meanwhile, the bottom of the main valve is ported by the passage 160 to the lower valve space 155, whence it can connect through the passage 163 to the return line 140.

- 20 25 The main valve 170 has a lower land 171, and an upper land 172. These are separated by a valving passage 173. In the illustrated upper position of the main valve, the power oil through the passages 102 is cut off by the lower land 171, and the upper cylinder 71 is connected through the passage 138 with the return line 89, which connects to the production oil space by way of the passage 140. This means that the upper part of the hydraulic motor piston is at production oil pressure. Upon reversal of the intermediate valve 150, the main 30 35 valve 170 will be driven downwardly. This will cut off the passage 89 and connect the power oil passage 102 with the cylinder passage 138 through the valve space 173. This will put power oil pressure onto the upper cylinder 71.

- 40 The top of the valve body passage is closed by a sealing plug 175 that also provides an upper limit to the movement of the main valve.

Operation

- 45 At the start, it is assumed that the power oil pipe 20 is connected to some suitable source of pressure on the surface such as a form of pump that can supply an adequate amount of oil under pressure for the present purposes. As a result, the pressure in the power cylinder 50 that is delivered from the power oil pipe 20 is the normal hydrostatic head of oil from the cylinder to the surface, plus whatever pressure is superposed thereupon by the pumping mechanism aforesaid. This pressure is constantly delivered from the power oil pipe 20 to the chamber 80, 55 thence by the passage 81 to the space 70 within the barrel 22. From this space it descends all the way down to just above the sucker rod pump connection, whence it can enter through the holes 66 into the lower cylinder 67 and act upwardly upon the effective lower area of the 60 piston 37 which, as understood, equals the inside diameter of the cylinder or barrel 46 minus the outside diameter of the connecting rod 31. This pressure acting upon the lower surface of the piston thereby tends to move the piston upwardly, carrying with it the connecting rod 31 65 which, in turn, is connected down to the sucker rod projection 26 and ultimately to the sucker rod pump (not shown).

The foregoing is not to say that the mere existence of power oil pressure within the cylinder 67 actually causes the piston to move upwardly because of conditions to appear. Whether or not the piston moves upwardly depends upon the conditions set by the valve apparatus.

In the position of the valves illustrated in Figure 11, the mechanical valve 110 is in its neutral position, since 75 it has been acted upon and released. Its last movement

was downwardly, in which case it would have ported power oil from the port 100 through the passage 144 to the upper valve chamber over the upper end of the intermediate valve 150. It correspondingly would have ported the lower valve chamber of the intermediate valve by way of the passage 143 and the passage 142 to the production oil at relatively low pressure, namely hydrostatic head of oil in the well. Since the power oil is at higher pressure, such action would have driven the intermediate valve to its lower position illustrated.

The lower position of the intermediate valve 150 ports power oil from the passages 101 to the passage 160 and to the lower valve actuating chamber of the upper valve 170. At the same time, the upper actuating pressure chamber of the main valve 170 is connected by the passage 161 to the return passages 165 and 140. This accounts for the upper position of the main valve 170 that causes the upper cylinder 71 to be ported to the return line. This condition is illustrated by the fact that the upper cylinder 71 is in continuous communication through centering spring cage 48, spacer 50, and passage 140 to the passages 85 that are connected into the well casing.

When the foregoing condition exists, the motor piston is acted on by power oil pressure at its underside and well casing hydrostatic head pressure at its upper side. While the piston area on the lower side of the piston is less than that on the upper side, this is more than overcome by the excess of power oil unit pressure over maximum production oil unit pressure. Consequently, the piston is driven upwardly.

In the illustrations, the piston has recently begun its upward movement, carrying with it the sucker rod. To show the greater pressure below the piston, the arrows pointing upward in the cylinder 67 are solid; to show lesser pressure on greater area, the arrows pointing downward in the cylinder 71 are in broken lines but more numerous.

As the piston 37 goes upwardly, it will carry the overtravel spring cage 39 upwardly with it, but it will not move the valve stem rod 120. Rather, it will reciprocate over that valve rod through substantially the whole stroke of the pump. This stroke may be in the order of five feet, for example. It is desirable to have sufficient oil passage space around the valve stem parts to avoid great pressure drop as the valve stem enters the oil-filled connecting rod and expels oil therefrom. In the illustrated design, the maximum pressure drop is about 2# as against 10# in the spring 126.

As the piston approaches the upper extreme of its movement, the actuator 41 will constitute an abutment to impinge upon the bottom end of the connector 121, which is secured to the rod 120, and which acts as a companion abutment. Thereafter, any further movement of the piston rod (which movement will continue until there is a reversing of the valves) will elevate the sleeve 125, and the valve stem 111 and the valve 110, moving the mechanical valve 110 to its upper position. In so doing, the upper end of the collar 121 abuts and elevates the lower centering spring guide 126, elevating it against the spring 126. In the upper position of the valve 110, as already noted, it ports power oil to the lower operating chamber of the intermediate valve 150 to elevate that valve, which, in turn, causes delivery of power oil to the upper side of the main valve 170 driving that valve downward. When the main valve 170 is driven downward to its lower position, the cylinder 71 is connected to power oil by way of the passage 102. This means that power oil is introduced by the passage 138 to the space below the valve body which is always in communication with the upper cylinder 71.

When the foregoing takes place, pressure is built up above the piston 37 while, at the same time, the power oil pressure remains the same below the piston. Owing to the fact that the effective area on the upper side of

the piston 37 is greater than that on the lower side, this admission of power oil pressure to the cylinder 71 causes the piston to start moving downwardly. Immediately it causes the actuator 41 to withdraw from the collar 121 so that the neutralizing or centering spring 126 may return the mechanical valve 110 to neutral position. However, the return of the valve 110 to neutral position merely provides a hydraulic lock on the intermediate valve, because in such position the lower actuating chamber of the intermediate valve is connected by way of the passage 143 to the land 132 of the mechanical valve 110, at which point it is blocked and trapped. At the same time, the upper operating chamber of the intermediate valve is connected by the line 144 to the land 131 of the mechanical valve 110, and is likewise hydraulically locked. By this arrangement, as soon as the mechanical pressure is relieved from the mechanical valve 110, it forthwith effects a hydraulic lock to hold the intermediate valve in the position to which it just previously has been moved. It, of course, will be understood that there is no mechanical relief on the mechanical valve until the main valve is shifted, because it requires a shift of the main valve to reverse the conditions of the motor so as to reverse the direction of movement of the piston. Also, the intermediate valve 150 is assured of movement to its full extreme before the hydraulic lock upon it is rendered effective. This will assure that, regardless of whether the mechanical valve is again neutralized prior to full movement of the main valve 170, there will be full movement assured because of the position of the intermediate valve.

The piston will then descend, and after the first brief part of its movement the valve stem 120 will not be moved, but the piston will reciprocate over the valve stem.

When the piston approaches the lower end of its movement on a downstroke, which is a position more or less as illustrated, it will cause the retainer 41 to approach the nut 123 which acts as an abutment. At the extreme of such downward movement, contact will be effected between the retainer 41 and the nut 123, so that the subsequent small downward movement of the piston will cause the valve stem 120 to be lowered from its neutral position, establishing the sequence of reversing the action previously mentioned of all three valves, and again connecting the cylinder 71 with the return line at production oil pressure, while leaving power oil pressure below the piston 37 so as to reverse the direction of the piston and drive it upwardly again. After the first brief part of the upward movement of the piston as aforesaid, the mechanical valve will again be permitted to neutralize under the influence of the spring 126, providing the same hydraulic lock but with the two upper valves in their opposite positions.

The foregoing represents the cycle of operation of the pump motor with its reversing valve apparatus. Since the pressure oil is always on the underside of the piston, and since there is a differential piston area, with mechanical valve reversals, the piston cannot hang up on dead center, even though no springs are provided. If, for example, the piston were on an upstroke, and it partly shifted the valves until pressure is partially admitted into the upper cylinder 71, a downstroke cycle is inevitable, because even the slowly entering pressure admitted through a partially shifted valve will ultimately build up to provide the downstroke. The main valve passage 173 should have an axial length insufficient to connect the pressure passage 102 with the return passage 89.

It is valuable to have the anti-stall feature, without springs. And the same structure of the small upstroke area and large downstroke area provides a relatively fast downstroke, which is the return stroke of the sucker pump.

11
Assembly

Among the especial features of the present invention are details of the arrangements for assembly and disassembly with minimum difficulty and a minimum diversity of tools.

Reference has already been made to the adjustment between the spacer tubes 24 and 241. The effect, which is accomplished by loosening the nut 40 and relatively moving the two spacer tubes 24 and 241, is to shorten the outer barrel of the pump at its lower end without shortening the connecting rod 31. The overall result of this is to cause the pump piston rod of the sucker pump to move closer to the end of the pumping cylinder on the compression stroke. This has such advantages as the automatic purging of the pump in the event of a vaporization of the liquid being pumped.

This adjustment is readily accomplished by putting a wrench around the spacer tube 241 at the opposed flats 64, and another wrench around the nut 40 to loosen the same. Thereafter, the two spacer tubes may be relatively twisted to get the proper extension or contraction of the length, followed by tightening of the nut.

The reversing of the valve may be caused to occur only at the extreme end of the movement of the piston—and hence of the sucker rod—by means of the adjustment of the two nuts 122 and 123, or of the collar 121. Normally, there is no need for adjustment of the collar 121 because it represents the relatively unadjustable upward movement of the mechanical valve 110.

It is fairly evident that the overtravel spring 40 will prevent any undue strain on the parts should there be an overtravel before a shift can occur and in the event of maladjustment of the foregoing parts.

Ordinarily, in servicing the pump mechanism and motor, the first thing to be done is to separate the sucker rod pump from the hydraulic motor. As the equipment is raised to the surface, an appropriate tool may be slipped around the proposed flats 64 in the lower spacer tube 241, which tube will extend outwardly so that the apparatus may be hung on the surface superstructure of the well. Then the joint between the sucker rod pump 25 and the lower tubular extension 241 may be separated. The pull rod 26 of the pump will remain attached to the connecting rod 31 by the coupling 30.

The preferable way to proceed for separation of the pull rod 26 is to loosen the lock nut 40 and separate the lower tubular extension 241 from the upper tube 24. Then if the pump piston is pulled downwardly, the extension tube 241 may move to expose the coupling 30 which then may be separated from the tubular connecting rod 31. Thereupon, the sucker rod pump and the hydraulic motor are separated.

If it be desired then to service the inner mechanism of the pump, the preferred procedure involves, first, a removal of the upper head 21 by threading it out of the outer barrel 22. Thereupon, the lower coupling or packing retainer 23 can be removed and, if desired, drawn with any parts below it that are attached to it, off the lower end of the connecting rod 31, although this latter may not be necessary at that point. Then, preferably, a tool is applied within the outer barrel 22 to force outwardly upon the packing retainer and cylinder closure member 43. Or the member 43 may be removed downwardly and the tool applied against the inner barrel 46, and also the rod 31. When these parts are pressed upwardly, the inner barrel 46 abuts against the centering spring retainer 48 which, in turn, abuts against the sleeve member 55 of the valve so that all of those parts together are forced out the upper end of the outer barrel 22 and emerged therefrom successively. In this operation, it is also preferred to force the connecting rod 31 upwardly, because it is not removable from the valve stem 120 and therefore would cause a separation of parts within the pumping and valving sections of the mechanism.

12

If the servicing is to be done upon the valving elements, these alone may be forced out the upper end of the outer barrel 22, and the valve, including its sleeve 55, withdrawn off the retainer 50. The mechanical valve 110 does not necessarily move out with the valve body. However, it may readily be removed from the head of the extension 111 by slipping it laterally through the slots 114 and 115, when the spacer retainer 50 is pulled away from it.

10 The successively lower parts may be serviced in like manner by being forced out the upper end of the outer barrel 22. The retainer 50 may be lifted out of the retainer 48. The mechanical valve operating mechanism may be serviced by forcing the parts upwardly until the 15 overcenter spring cage 39 projects and can be removed. This will free the lower collar 123 for removal, whereupon the valve stem 120 is freed and all of the parts may be removed, adjusted and serviced.

It is possible to separate the valve centering mechanism 20 by removing the setscrew holding the valve stem portion 120 in the collar 121.

The foregoing illustrates how the parts of this hydraulic motor pump actuating means may be disassembled for servicing. The reassembly constitutes an obvious reversal 25 of the disassembly above described. It is also apparent how the various packing elements may be replaced in disassembly and reassembly process.

Thus, in general, there are three parts to the whole pump apparatus. There is the lower sucker rod pump 30 subassembly not illustrated, but merely represented in the drawings. There is the hydraulic actuating motor, and there is the control valve. The sucker rod pump can be removed from the lower end of the actuating motor, and the valve can be removed from the upper end of the actuating motor. Finally, the actuating motor itself may be disassembled by being drawn out of its barrel.

By the foregoing description, it is not intended to restrict the order of assembly or disassembly, or to require that it be through the upper end of the barrels other than 40 is obviously necessary from the constructions involved. However, the fact that the assembly may be made largely through the upper end of the barrel constitutes a valuable feature of this arrangement.

What is claimed is:

45 1. In a well pump: a power cylinder; a piston reciprocable therein and provided with a tubular cage; valve means to control flow of fluid under pressure to the piston to effect reciprocation of the piston, the valve means including a valve movable in the same directions as the piston; a valve stem coaxial with the piston and extending into the tubular cage of the piston; first abuttable elements on piston and stem within the piston comprising a ring-like retainer to be engaged at the end of a stroke in which the piston moves in a first direction to withdraw 50 from the stem, the elements preventing such withdrawal; second abuttable elements on piston and stem comprising a collar to be engaged at the end of an opposite stroke when the piston moves in its second direction; and yieldable means including a spring surrounding the stem and yieldably holding the retainer a maximum distance toward the collar so as to resistingly yield when the elements are abutted as aforesaid, to permit overtravel of the piston relatively to the valve.

2. The combination of claim 1, wherein there are two 65 such ring-like retainers surrounding the stem and within the cage, constituting two of the abuttable elements; wherein the spring acts to separate them the maximum distance permitted by the cage; and wherein the retainer opposite the collar projects from the cage to engage with 70 the other abuttable element on the stem.

3. In a motor usable in a well for a reciprocable pump: a long outer tubular barrel; a head thereon having a power fluid passage leading therethrough to the inside of the barrel adjacent the wall thereof, and a production 75 fluid passage leading from outside the upper part of the

pump to the inside of the barrel at the middle part of the top; a cylindrical valve device attached to the head to connect the production fluid passage into the valve and to separate off the power fluid passage to outside the valve; closure means at the lower end of the outer barrel; an inner barrel within the outer barrel below the valve device; means connecting the upper end of the inner barrel and the valve providing communication with the lower end of the valve device and the inside of the inner barrel, there being a power fluid space between the outer and inner barrel connecting with a space between the outer barrel and valve device and with the power fluid passage; ports through the inner barrel adjacent the lower end; a piston in the inner barrel with a connecting rod depending therefrom and extending through the closure means, the valve having means including a valve movable up and down, to alternately connect the upper side of the piston with the power fluid passage and the production fluid passage, the piston having different areas above and below; a valve stem depending from the movable valve and into the piston; and two pairs of spaced abutment means between the valve stem and the piston to cause movement of the valve when the piston reaches the two extremes of its strokes.

4. The combination of claim 3, wherein the outer barrel is separable from the head and the lower closure; and wherein the valve device, the inner barrel, and the means connecting them are releasably clamped between the head and the lower closure, and may be ejected from the end of the outer barrel when the head is removed.

5. In a motor usable in a well for a reciprocable well pump: an outer barrel; a removable barrel head; a removable lower barrel closure; a valve device in the barrel; an inner barrel containing a piston within the outer barrel; and means connecting the inner barrel and valve device and connecting means in axial alignment within the outer barrel to hold them rigidly in place, and the aligned parts aforesaid being removable through the end of the outer barrel when the head and closure are removed.

6. The combination of claim 5, with a valve stem depending from the valve device to the piston, and spaced pairs of abutment elements between the piston and stem to provide movement of the stem at the ends of the strokes of the piston.

7. The combination of claim 6, with the connecting means between the valve device and the inner barrel comprising a centering spring cage; a pair of axially spaced opposed fixed abutments within the cage; and a pair of opposed, substantially equally spaced abutments on the

stem, a pair of opposed spring guides surrounding the stem and a spring urging them apart, the guides being normally, yieldably engaged with the opposed abutments on the stem and fixed.

5 8. In a motor usable in a well for a reciprocable pump: an outer barrel; a motor cylinder and piston in the barrel; a connecting rod depending from the barrel; a spacer tube device depending from the barrel around the connecting rod; and connections for removably attaching a sucker rod pump at the bottom of the spacer tube device and for removably attaching a pull rod of the pump to the connecting rod of the motor, the spacer tube device including telescopic adjusting parts by which the length of the spacer tube may be adjusted without changing the length of the connecting rod and pull rod.

10 9. In a motor usable in a well for a reciprocable pump: an outer barrel; a motor cylinder and piston in the barrel; a connecting rod depending from the barrel; a spacer tube device depending from the barrel around the connecting rod; connections for removably attaching a sucker rod pump at the bottom of the spacer tube device and for removably attaching a pull rod of the pump to the connecting rod of the motor, the motor cylinder comprising an inner barrel separate from the outer barrel; a valve device 15 above the inner barrel; and removable parts closing the ends of the outer barrel, the pump and motor device being connectible by connecting the tubular extension of the outer barrel to the pump and the connecting rod to the pull rod, and the valve device and inner barrel being separable from the tubular extension upon removal of a removable part for closing the end of the outer barrel.

20 10. In a pump motor for a well: an outer barrel having means at its lower end for connection to a pump; a fluid cylinder and piston in the outer barrel providing fluid pressure chambers above and below the piston; a valve device above the piston including a valve stem depending from the device, the stem extending down to the piston and being connected against removal therefrom; one having a head and the other having a laterally open 25 slot into which the head may be slipped to be held against separation by axial forces; and means rigid with the barrel to hold the parts against lateral movement that would separate them.
